Primary Examiner — Kevin K Rudzinski*Assistant Examiner* — Amber J Rabie(74) *Attorney, Agent, or Firm* — MUNCY, GEISSLER, OLDS & LOWE, P.C.(57) **CLAIM**

We claim the ornamental design for a tool box, as shown and described.

DESCRIPTION

FIG. 1 is a top, front, right perspective view of a tool box showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom, rear, right perspective view.

The broken lines in the drawings illustrate portions of the tool box which form no part of the claimed design.

The dot-dashed line in the figures defines the boundary of claimed design and forms no part of the claimed design.

1 Claim, 7 Drawing Sheets(56)
